New York, N. Y.

Application June 13, 1942, Serial No. 167,230

Term of patent 3½ years

To all whom it may concern:

Be it known that we, Stanley S. Harris and Shenghwa Hong, citizens of the United States and China, respectively, both residing at New York, in the county of New York and State of New York, have invented a new, original, and ornamental Design for a Navy Chess Game Board, of which the following is a specification, reference being had to the accompanying drawing, forming a part thereof.

In the drawing:

Fig. 1 is a top plan view of a navy chess game board, showing our new design; and

Fig. 2 is an end elevational view of the same.

We claim:

The ornamental design for a navy chess game board, as shown.

STANLEY S. HARRIS.
SHENGHWA HONG.
